TYPE RETAINING PLATE

Frank H. Poeppelmeier, Dayton, Ohio, assignor,
by mesne assignments, to Set-O-Type Manufacturing Company, Cleveland, Ohio, a corporation of Delaware

Application August 6, 1931, Serial No. 555,635

11 Claims. (Cl. 101—270)

This invention relates to new and useful improvements in type retaining plates.

It is one of the principal objects of this invention to provide punched and formed plates to receive type for names and addresses for mailing lists, directories and other media where it is necessary to make changes and substitutions.

It is another object of my invention to provide such a type receiving plate that may be compactly assembled or nested with other similar plates for placement in stacks so that they may be conveniently filed in cabinets.

It is another object of my invention to provide type retaining plates that may be easily applied to rotary or flat bed presses. These plates are formed not only to receive the type channels, but also cards containing the name and address, or other matter which is represented by the type set up in those channels.

Other important and incidental objects will be brought out in the following specification and particularly set forth in the subjoined claims.

In the accompanying drawing, Figure 1 is a top plan view of my type retaining plate. Figure 2 is a sectional view of two of said plates, showing how they may be assembled after type has been placed within them. Figure 3 is an end view of one form of type channel. Figure 4 is an end view of another form of type channel. Figure 5 is an enlarged sectional view taken through the type retaining plate on the line 5—5 of Figure 1. And Figure 6 is an enlarged sectional view taken through the same on the line 6—6 of Figure 1.

Referring to the accompanying drawing for a detailed description of my invention, the numeral 1 designates a rectangular type receiving plate punched from suitable metal and formed near its top edges with grooves 2—2. Beyond these grooves the ends of the plate are turned downwardly to form flat inwardly inclined sides 3 that terminate at their lower edges in upturned reinforcing flanges 4.

These flanged lower edges on the sides 3—3 of each plate 1 permit it to be mounted on a similar plate by inserting those flanged edges in the grooved portions 2—2 respectively of the second plate. (See Figure 2.)

It is thus possible to compactly stack a number of these plates for convenient filing in a cabinet, not shown.

At one end of the plate a horizontal tab 5, parallel and closely adjacent the groove 2, is struck up for the insertion beneath it of the flanges 6 on a type channel 7. Parallel and

closely adjacent to the opposite groove 2, a flat vertical projection 8 is formed, having a horizontal flanged portion 9 to engage the top portions of the opposite ends of the type channels 7, whose flanges 6 are inserted beneath the tab 5. (See Figures 1, 2 and 5.)

As shown, the type channels 7 are split tubes of substantially rectangular cross-section and the flange 6 is an extension of the base portion of such split tube. When these flanges are first inserted beneath the tab 5 the latter has the position shown in dotted lines in Figure 5. It is then punched down to the full line position shown in that figure to tightly hold the channels 7 in place upon the type retaining plate 1, being assisted by the horizontal flanges 9 on the vertical side portions 8.

Curved lugs 10 are punched out of the plate 1 immediately in front of the position to be occupied by the first type channel 7 inserted in said plate to act as alining stops for said channel. (See Figures 1, 2 and 6.)

The flanged ends of the channels 7 are now open to receive type for the purpose of setting up a name and address, or other desired matter.

Beyond the tab 5 a pair of similar tabs 11 and 12 are struck up from the plate 1, one near each groove 2 to receive a card 13. Upon this card is typewritten the name and address which is represented by the type 10 within the channels 7. This card may be easily taken out for changes or alterations.

Punched outwardly from the type retaining plate 1, along its inner edge is a series of loops 14 to receive the conventional colored classification tabs 15. (See Figures 1 and 6.)

While in Figures 1, 3 and 6, I have shown the type channels 7 formed with horizontal flanges 6, at their top edges, to fit the grooves of a type 10, such as is illustrated in dotted lines in Figure 3, I do not desire to be limited to such a type channel. For example, in Figure 4 I have shown a type channel 17 with the flanges 16 turned downwardly at their inner ends to form vertical projections 17a adapted to fit a type 18 formed with a side groove adapted to receive these projections.

It will be seen from the above description and the accompanying drawing that I have provided a type retaining plate which may be manufactured at low cost by punching and forming it from suitable metal.

To this type retaining plate a series of type channels may be firmly secured in proper alinement in front of means punched from that plate

to receive a card bearing the indicia represented by the type in said channels.

At their side edges these type retaining plates are formed with flanged projections and grooves 5 to permit them to be compactly stacked for convenient filing in a cabinet. When it is desired to change a name or address on one of these plates, it may be easily withdrawn from the cabinet for the purpose of making the proper type and card 10 substitutions.

I do not wish to be limited to the details of construction and arrangement herein shown and described, for any changes and modifications may be made therein within the scope of the sub- 15 joined claims.

Having described my invention, I claim:

1. A type retaining means comprising a plate, a plurality of type channels, bottom flanges on said type channels at one end thereof, a tab at 20 one side of the outer surface of said plate beneath which the flanges on said type channels are inserted, leaving their flanged ends open to receive type, and a flanged projection on said plate, closing the other ends of said type channels and co-operating with the tab in firmly securing the 25 channels to the plate.

2. In a device of the character described, the combination of a holder, a set of hollow members each having inwardly projecting edge flanges 30 with a longitudinal opening along the top side, said members being side by side on the holder, means for fastening the members to the holder at the opposite ends, said fastening means serving to block the entrance to the members at one 35 end while leaving the other end unobstructed.

3. In a device of the character described the combination of a holder, a set of split tubes mounted thereon, each adapted to hold a row of type in its opening, means comprising a permanent part of the holder for engaging the top 40 of the tubes at one end thereof, and means on the holder for engaging the tube at the bottom at the other end.

4. The combination of a holder, a set of individual split tubes mounted side by side on the holder, the holder having an upstanding portion 45 extending across the ends and overlapping the tops of the tubes at one end, and means for retaining the tubes at the other end while allowing access thereto.

5. The combination of a holder, a set of individual split tubes mounted side by side on the holder, the holder having an upstanding portion 50 extending across the ends and overlapping the tops of the tubes at one end, the tube having an extension at the other end, and the holder having a lip overlying the extension.

6. The combination of a holder, a set of individual split tubes mounted side by side on the holder, the holder having means for retaining the tubes at one end, there being an opening 55 in the holder beyond the other end of the tube, the tube having an extension projecting

from its base portion and offset downwardly to occupy the opening, and the holder having a lip offset upwardly from the opening and now overlying the extension.

7. A type retaining means comprising a plate, a plurality of type channels, projections at the side edges of said plate for securing the type channels in alignment thereon, the plate projections at one side overlapping base extensions 10 of the channels, to leave that end of the channels open to receive type, the projections on the plate on the other side overlapping the tops of said type channels to prevent exit of type therefrom.

8. A type receiving means comprising a plate, 15 having means for carrying type lines, said plate being formed with grooves in its top surface, one on each side of, and at right angles to, the type lines, the side portions of said plate beyond 20 the grooves inclining downwardly and inwardly, to a region a considerable distance below the grooved portions of the plate, and reinforcing flanges turned upwardly from the lower edges 25 of said downwardly and inwardly inclined sides for the purpose specified.

9. A device of the character described, comprising a holding plate and a set of printing lines thereon, said plate being formed with upwardly facing open grooves extending crosswise of the printing lines and beyond the ends thereof, and with foot portions lying below that part of the plate carrying the grooves and directly beneath the grooves, whereby when a series of said devices are stacked the foot portions of one device may 30 occupy the grooves of the device next below it.

10. A device of the character described, comprising a plate, a set of individual type holders mounted thereon, the plate extending in each direction beyond the ends of the type and being then bent downwardly and upwardly to provide 40 transverse upwardly facing open grooves, the plate beyond the grooves being then bent downwardly and brought into a region directly beneath the grooves at least as great a distance below that part of the plate carrying the grooves as is the height of the type holders, so that a series of 45 said plates may be readily stacked.

11. A type receiving means comprising a plate, a set of split tubes mounted side by side on an intermediate region of the upper surface of the plate, and extending a considerable distance above the general plane of said plate, said plate being formed with open grooves in its surface, one 50 beyond each end of, and at right angles to, the type channels, the side portions of said plate beyond the grooves inclining downwardly to a region considerably below that portion of the plate carrying the grooves to provide feet to enter the corresponding grooves of a similar plate, whereby they may be assembled in a stack for 55 storage.

FRANK H. POEPPELMAYER.
